(57) **CLAIM**

The ornamental design for a heat exchange tube, as shown and described.

DESCRIPTION

FIG. 1 is a front, right perspective of the heat exchange tube showing our new design;

FIG. 2 is a front view thereof, the rear view being a mirror image thereof;

FIG. 3 is a left side view thereof, the right side view being a mirror image thereof;

FIG. 4 is a top plan view thereof, the bottom plan view being a mirror image thereof; and,

FIG. 5 is a reference view thereof illustrating a state in which the subject design is combined wherein the broken lines shown are for illustrative purposes only and forms no part of the claimed design.

1 Claim, 4 Drawing Sheets

FIG. 1

FIG. 2

FIG. 3

FIG. 4

FIG. 5
